HUBERT REISER AND FRANZ REISER, OF GUTTENBERG, NEW JERSEY

BROOM BRIDLE

Application filed April 18, 1928. Serial No. 270,870.

This invention relates to devices for maintaining brooms, of ordinary types as commonly used for floor sweeping, in proper condition for operation.

5 Brooms, as usually constructed of broom corn straws, include a handle set firmly in the upper or head portion of the broom, which is laced, sewed and wire bound above its curved main portion that blends into a wide but thin 10 bush-like element in which the straws are unconfined except at their upper ends; consequently spreading outwardly at the bottom and particularly at the narrow edges takes place.

15 This condition occurs more rapidly if the broom is allowed to stand upright on its bottom and is aggravated if the broom is moistened, the straws readily bending by reason of the weight of the broom.

20 Various expedients have been tried to avoid these conditions, under which the broom soon deteriorates, nearly all consisting of channelled elements constrained by helically wound springs which extend outwardly from 25 the sides and edges of the broom and act unpremeditatedly to scratch and mar the finish of furniture legs, mop boards and other objects with which they are brought into forcible contact in using the broom.

30 Another disadvantage that such metal springs have is that if stretched beyond their elastic limit they become useless and are not conveniently replaceable.

Having these matters in view, it is one of 35 the objects of this invention to provide a bridle, adjustable at will over the lower portion of the broom, and in which the constricting elements are not only elastic but flat, closely adherent and wholly incapable of 40 damaging any object with which they may be brought in contact.

A further feature is in the provision of a bridle by which a broom may be maintained in its original normal condition until worn 45 out, the bridle being attractive in appearance, inexpensive to construct and easy to apply.

Another aim is to produce a broom bridle applicable alike to thick and thin brooms, as well as to brooms of various widths.

50 These several advantageous features are

accomplished by the novel construction and combination of few and simple parts, as hereinafter described and shown in the accompanying drawing, forming a material part of this disclosure, and in which:—

55 Figure 1 is a plan view of a conventional floor broom showing an application of the invention.

Figure 2 is a perspective view of the bridle in detail.

60 Figure 3 is a transverse sectional view taken on line 3—3 of Figure 2.

Figure 4 is a perspective view of a modified form of bridle.

65 Figure 5 is a transverse sectional view taken on line 5—5 of Figure 4.

As usually constructed, the broom consists of a long handle, designated by the numeral 10, the same being rigidly set in the center of the essentially solid upper portion of the 70 broom head 11, wired as at 12 and sewed at 13.

The broom head is curved downwardly to blend into the divergently inclined rounded edges 14 and flat sides 15 of the narrow main portion of the broom between the edges, the 75 bottom being flat and at right angles with the handle, and as the broom straws are unsupported below the seam 13, except by mutual contact, are easily distorted, particularly when in a moistened and hence softened condition.

70 The simple form of bridle, shown in Figures 1 to 3 is composed of two sheet metal shells 16, essentially semi-cylindrical in cross-section and of a length compatible with the broom head to which they are applied, preferably to extend from near the bottom nearly to its rigid upper portion, these shells being applied to the inclined narrow edges to which 80 they are conformably curved.

85 Each shell is sheared centrally in its end portions to produce pairs of opposed loops or catches 17 offset slightly outward and open along their sides and proximate edges.

90 Encircling the body of the broom and shells 16 are heavy, endless, flat rubber bands 18 passed through the loops 17 to be clasped by them and held in adjusted position, these bands obviously permitting self-adjustment 95 of the shells to suit the inclined edges of the 100

broom and closely embrace the broom straws, preventing undue flexing and maintaining the broom in its initial shape and appearance.

The modified form of bridle, shown in Figures 4 and 5, presents the same general characteristics of close conformation and in addition is adapted to suit brooms of varying thickness.

This is accomplished by making the edge 10 confining shells in two longitudinal sections 20-21 disposed at the edge corners, these shells having loops 22-23 at their end portions in which are engaged the bands 24 holding the shells in close contact with the broom 15 body.

It is to be noted that the bands present a 20 soft cushion effect if brought in contact with an object by the broom, incapable of abrading or doing injury and further, such bands 25 are inexpensive and easily procurable.

Although we have described the preferred 30 embodiment of our invention, it is understood that minor changes in construction and details thereof may be made without departing 35 from the spirit or scope of the hereto appended claims.

Having thus described our invention, what 30 we claim as new and desire to secure by Letters Patent, is—

30 1. A broom bridle comprising elongated guards fitting the edges of the broom, loops extending from said guards near their end portions, said loops being open at their proximate ends and at their sides, and endless flat 35 rubber bands encircling the broom and said guards and clasped by said loops.

2. A broom bridle comprising pairs of metal elongated guards curved to conform to the edges of a broom each pair being divided 40 longitudinally to produce uniform sections, integral clips on each section near the ends thereof, and endless flat rubber bands engaged by said clips to compress the guard sections on the broom.

45 In testimony whereof we affix our signatures.

HUBERT REISER.
FRANZ REISER.
